(57) **CLAIM**

I claim, the ornamental design for a bottle with bottle stopper, as shown and described.

DESCRIPTION

FIG. 1 is a front perspective view of a bottle and bottle stopper, showing my new design;

FIG. 2 is a front view thereof, the rear view being a mirror image;

FIG. 3 is a left side view thereof, the right side view being a mirror image; and,

FIG. 4 is a top view thereof.

1 Claim, 3 Drawing Sheets

FIG. 1

FIG. 2

FIG. 3

FIG. 4
